Fig. 4.

Fig. 3.

To all whom it may concern:

Be it known that I, Harry Lewis, a citizen of the United States of America, residing at Valhalla, county of Westchester, and State of New York, have invented a new, original, and ornamental design for a Wrapper for a Roll of Ribbon or the like, of which the following is a specification, reference being had to the accompanying drawing, forming part thereof, wherein:

I claim:

The ornamental design for a wrapper for a roll of ribbon or the like, substantially as shown.
